S. B. REDFIELD

PILOT VALVE FOR COMPRESSORS

Filed May 16, 1923

UNITED STATES PATENT OFFICE.

SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

PILOT VALVE FOR COMPRESSORS.

Application filed May 16, 1923. Serial No. 639,261.

To all whom it may concern:

Be it known that I, SNOWDEN B. REDFIELD, a citizen of the United States, a resident of Easton, county of Northampton, and 5 State of Pennsylvania, have invented a certain Pilot Valve for Compressors, of which the following is a specification, accompanied by drawing.

This invention relates to compressors, but 10 more particularly to pilot valves for compressor regulators.

Valves heretofore used for controlling the operation of compressor regulators, especially starting unloaders, have frequently 15 proved inefficient and unreliable for the reason that they have broken in a short time after installation, or have failed to operate the unloader positively to relieve the compressor of its load or to throw on the load 20 at the proper time.

The objects of this invention are to overcome the above difficulties by producing a valve mechanism which is simple in its construction and which will operate the un- 25 loader properly and positively on starting, and entirely relieve the compressor load on stopping.

Further objects of the invention will hereinafter appear, and to all of these ends the 30 invention is shown in the accompanying drawing, in which,

The figure is a vertical sectional view in elevation of a compressor unit with the un- 35 loader and pilot valves connected thereto, the parts being shown in running position.

Referring to the drawings, the unloader A is connected to the discharge line B of a compressor C between the compressor and the usual receiver D. The compressor com- 40 prises the cylinder E having the reciprocating piston F, adapted to be driven by any suitable source of power, as an electric motor (not shown). The compressor is pro- 45 vided with inlet valves G, the discharge valves H, and the discharge chamber J connected to the discharge line B.

The unloader comprises the valve casing K having the main valve chamber L sep- 50 arated from the outlet O by a partition P on which the main check valve Q is adapted to be seated for controlling the discharge from the casing. The check valve Q is pro- 55 vided with the spring R bearing on the valve and held by the cap S, which cap also forms a valve guide. The pressure in the

receiver tank D normally holds the main check valve Q to its seat when the compressor is idle.

The wall T of the casing K is provided with a valve seat U on which the relief valve V is adapted to be seated for controlling communication between the main valve chamber L and the atmospheric vent X, conveniently located in the side of the extension Y of the main casing K, in which the relief valve V operates. The relief valve V is preferably carried by a piston Z and has limited longitudinal movement relatively to the piston, being urged outwardly from the piston Z by a comparatively heavy 60 coiled spring a in the valve socket b, of sufficient strength to resist the full line pressure in the main valve chamber L and prevent the relief valve from opening from its seat U against the spring, due to said pressure when the valve is held to its seat by the combined spring pressure and fluid pressure behind the piston Z. The movement of the relief valve V is limited by the pin c passing through a transverse aperture d 65 in the valve, and secured at each end in the piston Z.

The piston Z, of the differential type, is provided with an enlarged head e forming a pressure area materially greater than the opposed pressure area when in its inward position on the face of the relief valve V, and pressure behind the piston head e will force the relief valve V to its seat U with sufficient force to compress the strong spring 70 a and also hold the piston head e firmly against the seat f in the extension Y of the casing, so that leakage of fluid past the piston from behind the piston head is shut off and prevented. The relative longitudinal movement or lost motion provided between the relief valve V and the piston Z 75 enables both the valve and the piston to be tightly seated on their seats U and f respectively.

A projection or stop g on the piston Z is adapted to bear against an adjusting screw h in the cap W, by means of which the initial starting position of the piston Z and relief valve V may be adjusted.

The unloader, so far described, prevents the fluid compressing load from coming up on the machine until the motor is up to full speed. During the starting period, fluid, as air, enters the main valve casing K at the 80 100 105 110

inlet side and leaves at the atmospheric vent X, and the main check valve Q holds back the air in the receiver D and pipe lines. When the compressor is started, the slight pressure built up in the main valve chamber L will force both the relief valve V and piston Z rearwardly and substantially all the air will pass out through the vent X to atmosphere. It is to be assumed that the 10 adjusting screw h has been set at such a point that the relief valve and piston move rearwardly and open the relief valve the required amount, so that when the compressor is up to full speed there will be a throttling 15 pressure of a few pounds as the air passes the relief valve V.

The loading of the compressor should be delayed until substantially full compressor speed is reached, and the unloading should 20 occur automatically just as or before the compressor stops entirely. In accordance with the present invention, to enable the unloader A to operate positively and to relieve the pressure on both sides of the compressor 25 piston F as the compressor stops I provide pilot valves which are connected to the compressor cylinder, and "in series" with the unloader.

In this instance, the pilot valves A' and 30 B' are connected by pipes (not shown) to the compressor cylinder E adjacent each end thereof. A pipe or tube 16 connects the extension Y of the main valve casing rearwardly of the piston Z with the port 15 in 35 the upper section of the pilot valve B' in order to permit pressure fluid to be relieved from or admitted to the rear of the piston Z. The pilot valve A' is in communication with the main valve chamber L through the pipe or tube 12, and the upper section of the pilot valve B' is in communication with the port 14 of the pilot valve A' by the pipe or tube 13. The unloader and pilot valves are thus 40 connected together "in series", the advantage 45 of such a connection being that the pressure on both sides of the compressor piston is relieved as the piston stops, and movement of the unloader piston Z is positively controlled.

The pilot valve A' is composed of upper and lower casing sections j and k respectively, which are held together in any suitable manner, as by bolts and nuts o. In the upper casing section j is located a downwardly seating ball check valve p which controls the passage of fluid from the main valve chamber L. A coil spring r holds the valve p to its seat when the compressor is idle. An upwardly seating ball check valve 55 s, maintained a predetermined distance from the valve p by a spacer pin t, controls the passage of pressure fluid to atmosphere through the port or vent u in the casing section j. The arrangement of the ball check 60 valves p and s and spacer pin t is such that

when one valve is seated the other is unseated. A piston v, movable in the casing section j, is provided with an enlarged head w, which is adapted to be moved to its seat x by pressure fluid from the compressor cylinder E. A plunger y is located in the piston v and has limited movement therein over a pin z, which passes through the transverse aperture y' in the plunger. The ends of the pin z are connected to the piston v. A comparatively heavy coiled spring 2 in the piston v normally holds the plunger y in its extreme extended position, so that when the piston v is moved forwardly and the enlarged head w is forced to its seat x, the plunger y will bear against and seat the ball valve s.

The check valve 6 in the lower casing section k is provided with the small port 7, and controls the outlet of pressure fluid to the 85 compressor cylinder. A coil spring 8 serves as a distance piece for the check valve 6 so that the valve will not be moved too great a distance from its seat.

The pilot valve B' is similar in its construction to the pilot valve A' just described, and description of one pilot valve is deemed sufficient for a clear understanding of the invention.

Assuming that the compressor is starting 90 or stopping and the compressor piston F is moving to the left, pressure fluid is forced from the compressor cylinder through the port 17 of the casing section k and moves the piston v upwardly, causing the enlarged 100 head w to be seated on its seat x, and thereby seating the ball check valve s to shut off the passage of fluid from the upper casing section j to atmosphere through the vent u. At the same time, the ball check valve p is 105 seated, ball check valve p will be unseated by means of the spacer pin t, and pressure fluid is permitted to pass from the main valve chamber L through the pipe or tube 12 into the pilot valve A', past the ball 110 check valve p, and to the pilot valve B' through the pipe or tube 13.

As the compressor piston F is on its suction stroke relative to the pilot valve B', pressure fluid in the lower casing section 115 passes from beneath the piston v through the port 18 in the check valve 19, and port 20 into the compressor cylinder E, and the piston v is moved downwardly by the combined action of the coil spring r', and the 120 entrance of air through the port u' in the upper casing section. The ball check valve p' is seated by the coil spring r', so that fluid pressure from the main valve chamber L is shut off and prevented. The ball check valve s' is accordingly unseated by the spacer pin t', and pressure fluid from behind the enlarged head e of the unloader piston Z passes through the pipe or tube 16 and 125 vent u' to atmosphere.

When the compressor piston moves to the right on starting or stopping, the operation of the pilot valves above described is reversed, and the piston v' and ball valves s' and p' in pilot valve B' will be in the upward position and pressure fluid from the space back of the piston Z will pass through the tube 16, past the ball valve p' in the pilot valve B' , through the tube 13 into the pilot valve A' , past the ball valve s , which will be in its unseated position, and out through atmospheric vent u . The ball valve p in the pilot valve A' will then be in its seated position, thereby cutting off the passage of fluid from chamber L .

During the time that the compressor is accelerated, the alternate rising and falling of the pistons v and v' in both pilot valves will continue until the compressor piston F has attained such a speed that there is insufficient time during the suction strokes of the compressor piston relative to each pilot valve alternately, for the fluid pressure in the space under the pistons v and v' to escape to the compressor cylinder. When this condition has been reached, fluid pressure in the space under the pistons v and v' will be sufficient to hold the pistons in their extreme upper position throughout the normal running period of the compressor. When the pistons are in their upward position the check valves s and s' are seated, and the check valves p and p' are unseated. Pressure fluid is therefore permitted to flow from the main valve chamber L through the pipe or tube 12, past the ball check valve p and spacer pin t in the pilot valve A' , through the pipe or tube 13 to the pilot valve B' , past the ball check valve p' and spacer pin t' , and through the pipe or tube 16 to the extension Y of the main valve casing. This pressure fluid forces the piston Z inwardly, thereby moving the relief valve V to its seat U shutting off the flow of pressure fluid from the main valve chamber L to atmosphere through the vent X .

Further increase of pressure back of the piston Z compresses the spring a and moves the enlarged head e of the piston Z to its seat f , thereby seating both the relief valve V and the piston Z . The relief valve V being thus closed, pressure fluid from the compressor cylinder passing into the main valve chamber L increases the pressure therein to such a point as to overcome the spring R of the main discharge valve Q , and fluid pressure in the discharge line O and receiver D , raises the check valve Q and discharges the pressure fluid from the compressor cylinder through the discharge line O into the receiver D .

On stopping of the compressor, during the slowing down of the piston F , sufficient time will be allowed on the suction strokes

relative to each pilot valve to allow the pressure fluid under the pistons v and v' to be discharged into the compressor cylinder. Thus the pistons v and v' will be permitted to move downwardly, allowing the ball check valves s and s' to be unseated and the ball check valves p and p' to be seated. This action takes place alternately in the two pilot valves on the alternate suction strokes. When the check valves s and s' are unseated, pressure fluid from behind the piston Z will be permitted to flow to atmosphere through the atmospheric vents u and u' alternately with each suction stroke of the compressor pistons, and at the same time the flow of pressure fluid from the main valve chamber L is shut off by the alternate closing of the ball check valves p and p' .

The unloader should be adjusted to unload as promptly as possible on stopping. To this end, washers 11 are provided in the lower sections of the pilot valve casings by which the volume under the pistons v and v' may be varied. With high pressures there is too great a volume of air under the pilot valve pistons v and v' to permit quick passage thereof through the small ports 7 and 18 in the check valves 6 and 19, respectively, for the compressor to unload before stopping. It therefore becomes necessary to remove the lower section of the pilot valve casings and insert a greater number of washers 11 in order to reduce the space or volume into which pressure fluid may enter. On the other hand, with low pressures it is necessary to increase the space or volume in the lower section of the pilot valves to prevent unloading during the running period and to delay the unloading until the compressor piston F has slowed down. To do this, the number of washers must be reduced.

In order to prevent the parts from falling out when the lower section k of the pilot valve A' is removed, I provide a screw 4 threaded into the upper casing section j and extending into an external circumferential groove 5 in the piston v , thereby limiting the rearward movement of the piston v . The pilot valve B' is provided with a similar limiting device for the pilot valve piston, as shown.

I claim:

1. A pilot valve for compressor regulators comprising a casing adapted to be connected to the compressor cylinder, a valve for controlling the admission of pressure fluid to the casing, a valve spaced from the admission controlling valve for controlling an atmospheric vent in the casing, a single means for actuating the said valves in one direction controlled by the pressure in the compressor cylinder, means for moving the valves in the opposite direction, and means

for varying the volume of pressure fluid admitted to the casing from the compressor cylinder.

2. A pilot valve for compressor regulators comprising a casing adapted to be connected to the compressor cylinder, a valve controlling the admission of pressure fluid to the casing, a valve controlling an atmospheric vent in the casing and operatively connected to the admission controlling valve, whereby when one valve is seated, the other valve is unseated, means controlled by the pressure in the compressor cylinder for actuating the valves in one direction, and means for returning the valves to normal position as the pressure in the compressor cylinder is reduced.

3. A pilot valve for compressor regulators comprising a casing adapted to be connected to the compressor cylinder, a valve controlling the admission of pressure fluid to the casing, a valve controlling an atmospheric vent in the casing and operatively connected to the admission controlling valve, whereby when one valve is seated, the other valve is unseated, means controlled by the pressure in the compressor cylinder for actuating the valve in one direction, means for returning the valves to normal position, as the pressure in the compressor cylinder is reduced, and means for varying the volume in one part of the casing into which fluid pressure is admitted whereby the movement of said actuating means is controlled.

4. A pilot valve for compressor regulators comprising a casing adapted to be connected to the compressor cylinder, a valve controlling an atmospheric vent in the casing, a valve controlling the admission of pressure fluid to the casing, means for maintaining said valves a predetermined distance apart, actuating means for the said valves controlled by the pressure in the compressor cylinder, whereby when one of the valves is seated, the other is unseated, and means for retarding the flow of fluid from the casing to the compressor cylinder.

5. A pilot valve for compressor regulators comprising a casing adapted to be connected to the compressor cylinder, a valve controlling the admission of pressure fluid to the top of the casing, a valve controlling an atmospheric vent in the casing, spacing means

between the valves, means for actuating said valves whereby when one of the valves is seated, the other valve is unseated, and a check valve for retarding the flow of fluid from the casing to the compressor cylinder.

6. A pilot valve for compressor regulators comprising a sectional casing adapted to be connected to the compressor cylinder, a ball check valve controlling the admission of pressure fluid to the upper section of the casing, means controlled by the pressure in the compressor cylinder including a piston and plunger, having limited movement in the piston for unseating said valve, and a check valve for retarding the flow of pressure fluid from the lower section of the casing to the compressor cylinder.

7. A pilot valve for compressor regulators comprising a casing adapted to be connected to the compressor cylinder, a check valve controlling the admission of pressure fluid to the casing, a check valve controlling an atmospheric vent in the casing, a spacer pin between said valves, means controlled by the pressure in the compressor cylinder for actuating said valves in one direction, and means for varying the volume in one part of the casing into which fluid pressure is admitted to one part of the casing, whereby the movement of said actuating means is controlled.

8. A pilot valve for compressor regulators comprising a sectional casing adapted to be connected to the compressor cylinder, a spring pressed ball check valve controlling the admission of fluid pressure into the upper section of the casing, a ball check valve controlling an atmospheric vent in the casing, a spacer pin between said valves, a piston in the casing, a plunger having limited movement in the piston and adapted to bear against and seat said atmospheric vent controlling valve, a check valve in the lower section of the casing adapted to retard the flow of pressure fluid from the casing to the compressor cylinder, and washers in the lower section of the casing for varying the volume into which fluid pressure is admitted, whereby the movement of the piston and plunger is controlled.

In testimony whereof I have signed this specification.

SNOWDEN B. REDFIELD.
